UNITED STATES PATENT OFFICE.

GEORGE LIPSCHUTZ, OF PHILADELPHIA, PENNSYLVANIA.

DESIGN FOR AN ELECTRIC-LIGHT FIXTURE.

Application filed January 4, 1927. Serial No. 20,278. Term of patent 3½ years.

To all whom it may concern:

Be it known that I, GEORGE LIPSCHUTZ, a citizen of the United States, and a resident of Philadelphia, county of Philadelphia, State of Pennsylvania, have invented a new, original, and ornamental Design for Electric-Light Fixture, of which the following is a specification, reference being had to the accompanying drawing, forming a part thereof.

The figures which show my new design are as follows:

Figure 1 is a perspective view of the electric light fixture; and

Figure 2 is a front elevational view thereof on a smaller scale.

I claim:

The ornamental design for an electric light fixture as shown.

GEORGE LIPSCHUTZ.
